V-BLOCK ATTACHMENT FOR MICROMETERS

Filed Oct. 1, 1945

UNITED STATES PATENT OFFICE

2,521,428

V-BLOCK ATTACHMENT FOR
MICROMETERS

Bennie Vizuete, Port Arthur, Tex.

Application October 1, 1945, Serial No. 619,559

1 Claim. (Cl. 33—167)

1

My invention presented herewith comprehends an improved micrometer, the primary object of which is to provide such an instrument with which accurate measurements can be made on tools such as reamers having an odd number of ribs or cutters.

Another object of this invention is to provide a micrometer with which accurate readings of work involving three surface points or odd multiples thereof may be made.

A further object of the invention is to provide a micrometer having a V-block hingedly connected thereto.

A still further object of my invention is to provide a micrometer so constructed and graduated as to give diameter of work in its reading without calculation.

Other features and advantages will become more readily apparent from the following description and the accompanying illustrative drawings in which:

Figure 1 is an elevational view of my micrometer.

Figure 2 is a longitudinal sectional view thereof shown partly broken off.

Figure 3 is a detail sectional view illustrating the mounting of a V-block.

Figure 4 is a detail sectional view of a collet nut, and

Figure 5 is a plan view thereof.

Due to the fact that a machinist cannot obtain a correct size of work involving odd cutter teeth, grooves, etc., with present micrometers without great difficulty and the use of independent V-blocks and without calculation, I have evolved the instant device whereby much time may be saved and whereby such work as that of finish grinding reamers and the like may be accomplished in less time and by less experienced mechanics.

My micrometer 10, consists of a C-member 11, having right-angular spaced apart aligning heavy arms 12 and 13, the former terminating in an enlarged internally screw-threaded cylinder 14, into which is threaded the solid externally threaded end 15, of a tubular internally threaded sleeve 16. Threaded into the sleeve 16, is the enlarged upper end 17, of a gauging spindle 18, which passes slidably through the bore 19, in said end 15.

Rotatably seated upon the upper end of the sleeve 16, is an actuating sleeve 21, having a knurled portion 22, and a beveled lower edge, which is scaled as indicated at 23, and is also provided with another scale 25, just above the bevel. The upper terminal 26, of member 21, is pro-

vided with a conic bore 21, into which projects the conic reduced head 28, of the said end 17, of member 18. The extreme terminal 29, of member 21, is annularly rabbeted as at 30, to form a seat for the annular flange 31, of a cap 32. Countersunk in the center of the cap and fixed thereto is the head 33, of a depending screw 34, which is threaded into the said conic member 28, whereby the member 17, will rotate with sleeve 21, for raising or lowering its spindle 18, for adjustment upon a piece of work.

Mounted on the spindle 18, is a collet nut 35, having a knurled flange 36, and a conic split tubular portion 37, threaded into the similarly formed threaded bore 38, in the bottom end, of the member 15. A knurled nut 40, is threaded upon the threaded end 41, of said member 15, between which and the said flange 36, is seated a washer 42. The purpose of the collet nut and its connections is to be able to fixedly secure the spindle 18, in an adjusted position.

The arm 13, is bifurcated to receive the hinge member 43, between the parts 44 and 45, of said arm, said member being a downwardly projecting tongue of a V-block or anvil 46, which may be swung over the end 47 of member 43, when not to be used. Projecting through slot 48, in part 45, is a pintle 49, of a bearing 50. Between the head 51, and the wall 52 of part 45, is an enlarged disk like part 52', thereof. A reduced central portion 53, of the pintle forms the bearing for the bore 54, of said hinge member 43. The still further reduced part 55, of the pintle extends through the slot 56, of part 44, of arm 13. The extreme terminal 57, of the pintle is threaded to receive a nut 58, bearing against wall 59, of said part 44, and which with the disk or flange 52', forms a clamp to hold the V-block in fixed position. The pintle 49, may be moved along the slots 48 and 56, to permit the V-block 46, to pass over the rounded portions 60, of said end 47.

The outer surface 61 of sleeve 16, is provided with a vertically disposed scale 62, correlative to scales 23 and 25, through which correct readings 45 may be taken directly from the instrument. 63, is a hand grip.

Great difficulty is experienced by a machinist, when for example, he has to finish grinding a reamer having an odd number of teeth or flutes 50 so that he cannot obtain a size with a regular micrometer because the flutes do not fall diametrically opposite each other. In some cases of this kind, a ring is bored out to the desired dimension and the reamer is ground till the ring 55 fits on over the flutes.

I have developed a micrometer for taking readings of work that involves three surface points or odd multiples of three (9-15, etc.). Taking such readings with a standard micrometer is not possible unless an accurate V-block is available and then the machinist must make necessary calculations to obtain desired reading.

My design utilizes the V-block principle, and the spindle is provided with the correct number of threads per inch to give a true reading directly from the instrument. It utilizes a 60° V-block which is hinged in place in order to accommodate large work without excessive opening of the instrument. The spindle is threaded with 26½ threads per inch which is the number necessary in this case to give a correct reading.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described my invention, that which I claim as new and desire to procure by Letters Patent is:

Attachment means for a V-block on one arm of a micrometer gauge, comprising a bifurcated portion in said arm having similar parallel flat plate parts, the corners of said plate parts re-

mote from said one arm being rounded, opposed slots in said parts extending longitudinally of the arm, a tongue on said V-block receivable between said parts and having a transverse aperture, a pintle extending through the slots in said parts and through said aperture, said pintle having one end threaded into a nut on one side of the arm and having a head abutting the other side of said arm, whereby the V-block is selectively secured to the arm in operative and inoperative positions.

BENNIE VIZUETE.
